SAMPLE RECEIVING PROJECTILE FOR SIDE WALL CORE SAMPLER

Vincent Dominick Leone, Beaumont, Tex.

Application January 17, 1956, Serial No. 559,746

1 Claim. (Cl. 255—1.4)

The invention relates to a sample receiving projectile for use in conjunction with a side wall core sampler of the type used to take samples of earth formations from the side walls of well bores, and it concerns more particularly a projectile for the purpose described having an inner lining comprising a split sleeve adapted to receive the sample as it is introduced into the projectile, the sleeve being made of spring steel and being capable of being expanded, due to its inherent resilience, upon removing the sleeve from the projectile with the sample contained therein, whereby the sleeve is disengaged from the sample and the sample may be recovered in one intact, unaltered piece.

There is a need in the oil industry for means for obtaining intact samples representative of earth formations at different elevations below the surface. Such samples, which are commonly referred to as cores, and which may have structures ranging from those which are relatively hard to those which are soft and friable, may be analyzed to determine quantitatively the nature of the fluids, whether gas, oil or water, with which they are saturated, as well as certain physical characteristics of the formation, such as its permeability and its porosity, which may affect the potential production of fluids from the formation.

One of the procedures followed in the search for petroleum involves drilling a well penetrating earth formations at different elevations below the surface. These formations are then evaluated for commercial oil or gas production. One of the methods used to evaluate such formations comprises obtaining small samples thereof. These samples, which are obtained from the side wall of the well bore, are commonly referred to as side wall samples or cores.

To obtain side wall core samples an instrument having a cylindrical housing, usually about 6 feet long and about 4 inches in diameter, is lowered in the drilled hole by means of a strong steel cable. Along one edge, and perpendicular to the long axis of the instrument, a plurality of sample receiving projectiles are fitted in line, one over the other. Usually there are about 30 of such projectiles per instrument. The projectiles each consist of a hollow cylinder having an open end and capable of receiving a sample of the material of the side wall formation upon shooting the cylinder into the formation.

The projectiles are each shot into the side wall formation by detonating an explosive charge placed in the instrument behind the projectile. The explosive charges are capable of being detonated electrically by remote control.

The projectiles are attached to the housing of the instrument by means of strong wires, so that after they have been fired they may be retrieved, with the core samples contained therein, upon raising the instrument to the surface.

The design of the sample receiving projectiles above referred to, and the dimensions thereof, may vary. A

2

number of such designs now exist. One of the factors which may affect the design of the projectile is the hardness of the formation from which a core is desired.

When the sample receiving projectile, with the core contained therein, is recovered at the surface, the removal of the core sample therefrom is always difficult. This difficulty is due in part to the fact that, when the projectile strikes the side wall of the well bore, a compression wave is set up in front of the projectile, thereby packing the core into the projectile under compression. Another factor affecting the manner in which the core is packed into the projectile is that, as the projectile is withdrawn from the high pressure area existing at the elevation from which the sample was taken, and as it approaches the surface, where atmospheric pressure exists, there is an expansion of the gases contained in the side wall core, which likewise tends to fit the core tightly in the projectile. When the side wall core is so tightly packed in the projectile, it is impossible to remove the sample from the projectile in one intact, unaltered piece. Since this is true, and considering that a great deal of money must be spent to obtain the sample, means for removing the sample from the projectile in one intact, unaltered piece will be of substantial benefit to the oil industry. If such samples are recovered in one intact, unaltered piece, core analysis tests may be obtained which will indicate accurately the productive characteristics and capacity of the formations sampled.

The invention contemplates an improved sample receiving projectile, for use in conjunction with a side wall core sampler of the type described, which permits the sample to be discharged from the projectile in one intact, unaltered piece.

A novel feature of the invention is a split sleeve which forms an inner lining for the projectile and receives the sample as it is introduced into the projectile. The sleeve is made of spring steel, and is capable of being expanded, due to its inherent resilience, upon removing the sleeve from the projectile with the sample contained therein, whereby the sleeve is substantially disengaged from the sample and the sample may be recovered in one intact, unaltered piece.

The invention will be readily understood by referring to the following description and the accompanying drawing, in which:

Fig. 1 is a diagrammatic elevational view of a side wall core sampler having incorporated therein a plurality of projectiles embodying the invention, and showing the respective positions of the several projectiles as the sampler is lowered into a well bore, before any of the projectiles have been fired;

Fig. 2 is a fragmentary view, on an enlarged scale, of a portion of the apparatus illustrated in Fig. 1, showing the position of one of the projectiles after it has been fired into the side wall of the well bore;

Fig. 3 is a sectional view, taken on a median line, of one of the projectiles;

Fig. 4 is a sectional view taken on the line 4—4 of Fig. 3; and

Fig. 5 is a perspective view of an inner sleeve which is an important feature of the projectile shown in Figs. 3 and 4.

Referring to Fig. 1 of the drawing, a side wall core sampler having an elongated cylindrical housing 1 is shown positioned in a well bore 2 and suspended from the surface by a steel cable 3. A plurality of projectiles embodying the invention, as hereinafter described, which are designated generally by the numeral 4, are each received in one of a plurality of longitudinally spaced openings 5 which are provided therefor in the wall of the housing 1, and extend outwardly therefrom. The

projectiles 4 are each connected to the housing 1 by a pair of wires 6, as hereinafter described, whereby the projectiles 4 may be retrieved after they have been fired.

Fig. 2 shows the position of one of the projectiles 4 after it has been fired, whereby it is shot from the housing 1 by detonation of an explosive charge placed behind it, in the usual manner, and lodges in the side wall of the well bore 2.

Referring to Figs. 3 to 5 of the drawing, each of the projectiles 4 has a tubular body 7, which is threaded internally at 8, adjacent one end thereof. An annular groove 9 is formed in the peripheral surface of the body 7 adjacent its opposite end. A plug 10, which has a threaded portion 11 for engagement with the threads 8, is received in one end of the body 7. The plug 10 has a pair of depressions 12 formed in the outer end thereof for engagement by a wrench.

A sleeve 13, which is made of spring steel and is split at 14, along one side thereof, is received within the body 7. One end of the sleeve 13 abuts the adjacent end of the plug 10, and the opposite end of the sleeve 13 is flush with the adjacent end of the body 7. The sleeve 13 is characterized by its resilience, whereby it must be compressed in order to insert it in the body 7, and is expanded upon withdrawing it therefrom.

An annular closure member 15, which has an inside diameter corresponding to the inside diameter of the sleeve 13 when compressed and an outside diameter larger than the outside diameter of the body 7, has an externally tapered outer end 16 and is enlarged internally at 17, adjacent its opposite end, to form an internal shoulder 18. One end of the body 7, with the sleeve 13 inserted therein, is received in the internally enlarged portion 17 of the closure member 15, and the adjacent ends of the body 7 and the sleeve 13 abut the internal shoulder 18.

The closure member 15 is detachably connected to the adjacent end of the body 7 by an O ring 19, which is made of spring steel and is split at 20. The O ring 19 is received partly in the annular groove 9 and partly in an annular groove 21, which is formed in the inner wall of the closure member 15 and is aligned with the groove 9. The O ring 19 is characterized by its resilience, whereby it is urged outwardly in engagement with the groove 21. The depth of the groove 9 is such that the O ring 19, when compressed, is capable of being disengaged from the groove 21.

A plurality of circumferentially spaced openings 22 are formed in the body 7 adjacent the threaded end thereof, which constitutes the rearward end of the projectile 4 as it is fired, as shown in Fig. 2. A plurality of circumferentially spaced openings 23, which are aligned with the openings 22, are formed in the wall of the sleeve 13. Drilling fluid, with which the well bore 2 and the interior of the sleeve 13 may be filled at the time the projectile 4 is fired, may be displaced from the sleeve 13 through the openings 22 and 23 upon impact of the projectile 4 with the side wall of the well bore 2, whereby the material of the side wall is caused to enter the sleeve 13 through the opening in the closure member 15.

A pair of threaded plugs 24 are received in diametrically opposed threaded openings 25 provided therefor in the wall of the body 7, forwardly of the openings 22.

The wires 6 are each connected at one end to one of the plugs 24, and at its opposite end to one of two threaded plugs 26 which are received in threaded openings provided therefor in opposite sides of the housing 1.

In taking the sample, the sample passes through the opening in the closure member 15 and is received within the sleeve 13. At the surface, the sleeve 13 is removed from the body 7 with the sample which it contains. Upon removal of the sleeve 13 from the body 7, the sleeve 13 springs out slightly, due to its inherent resilience, and expands enough to release the pressure on the sample. With the pressure released, the sample may be removed from the sleeve 13 in one intact, unaltered piece.

The closure member 15 prevents damage to the sleeve 13 when the projectile 4 strikes the side wall of the well bore 2. The O ring 19 retains the closure member 15 in engagement with the body 7 as the instrument is lowered in the well bore 2, but is capable of releasing the closure member 15 from the body 7 if the closure member 15 should become caught in the side wall after the projectile 4 has been fired. The closure member 15 is expendable, and may be left in the side wall of the well bore 2.

The invention may be modified in various ways without departing from the spirit and scope thereof.

I claim:

In an instrument for taking samples of earth formations from the side walls of well bores, a sample receiving projectile capable of being shot from the instrument whereby it is forced into an adjacent formation, the projectile comprising an open ended tubular body, an inner lining consisting of a split sleeve received in the body and capable of receiving a sample of the material of the formation, upon firing the projectile, the sleeve being made of spring steel and being capable of being expanded, due to its inherent resilience, upon removing the sleeve from the body with the sample contained therein, whereby the sleeve is substantially disengaged from the sample and the sample may be recovered in one intact, unaltered piece, an annular closure member detachably connected to one end of the body, the adjacent ends of the body and the sleeve being received in an internally enlarged end portion of the closure member, the body and the closure member having mutually aligned annular grooves formed in the adjacent surfaces thereof, and a split O ring received in the annular grooves, the O ring being made of spring steel and being capable of being expanded, due to its inherent resilience, whereby it is disposed partly in one of the grooves and partly in the other, the depth of the groove formed in the body being such that the O ring, upon being compressed, may be disengaged from the groove formed in the closure member whereby the closure member may be detached from the body.
